UNITED STATES PATENT OFFICE.

FRANK S. BALLARD, OF BURLINGTON, VERMONT.

MATCH-SAFE AND AUTOMATIC LIGHTER.

SPECIFICATION forming part of Letters Patent No. 396,135, dated January 15, 1889.

Application filed April 21, 1888. Serial No. 271,378. (No model.)

To all whom it may concern:

Be it known that I, FRANK S. BALLARD, a citizen of the United States, residing at Burlington, in the county of Chittenden and State 5 of Vermont, have invented certain new and useful Improvements in Match-Safes and Automatic Lighters, of which the following is a specification, reference being had therein to the accompanying drawings.

- 10 My invention relates to improvements in match-safes and automatic lighters; and it consists in the combination and arrangement of parts, which will be more fully described hereinafter, and pointed out in the claims.
- 15 In carrying my invention into operation I preferably use that class of matches which are either manufactured in blocks, in which the matches are not entirely unseparated at one of their ends and a row of these matches 20 placed in the safe unseparated, or that class of matches where they are cemented in rows to a card. By this means a row of matches is placed in the safe, saving the trouble of placing them one at a time in place.
- 25 The objects of my invention are, first, to provide a safe in which a card of matches may be placed ready for instant use without the labor of first splitting them apart; second, to so arrange the matches in the safe that it 30 shall be impossible to use more than one at a time, which shall be automatically lighted, thus avoiding the unnecessary waste which attends the use of ordinary match-holders, and, third, to so construct the operative mechanism that 35 it shall be of the simplest and cheapest character consistent with the successful operation of the device, and easily reached for purposes of adjustment or repair.

In the device shown in the drawings similar letters indicate like parts throughout the several views.

In the drawings, Figure 1 is an edge view of a safe embodying my invention. Fig. 2 is a side elevation partly broken away. Fig. 3 45 is a detached perspective of the knife and follower. Fig. 4 is a longitudinal section through the slide B.

A is a case made of any suitable material. It is designed to contain the operating mechanism which automatically presents the card 50 of matches inclosed therein to the separating

device, by the downward movement of which each match is severed from the card or split apart, and is then automatically forced upward with such rapidity, by means of a spring- 55 actuated follower, that its head or dipped end is brought into frictional contact with a rough surface, thereby producing immediate combustion. The match thus ignited is held lighted ready for convenient use. 60

B is a slide designed to move laterally in a slot, b, across the upper part of the case A. Its lower extremity when in position rests and slides upon a recessed shoulder, d, formed upon the upper interior face of the transverse 65 support C. Slide B is moved backward by means of the hand-knob e in its upper end, which projects above the top of the case A. It is forced forward automatically by the spring-actuated bifurcated lever D, in contact 70 with the fixed pin f in the projection g, which is secured across its interior face in such a manner as to prevent any tipping of the slide B when in motion, as the movement of the projection is confined between the upper and 75 lower edges of the recess b across the support C.

E is a metallic rod which terminates in the hooked knife x at its upper extremity.

The lever D is pivoted at its lower end to the interior face of the frame A, and is forced 80 outward at its upper end by the spring M, which engages its lower end below the pivotal point. When the slide B is moved inward to allow matches to be placed in the case, the upper end of the lever D, which engages the 85 slide, is also moved inward against the tension of the spring M.

The knife-rod E and its accompanying follower H are secured to the base F, which moves perpendicularly in the groove G at the side of 90 the case, the movement of the rod and follower being confined to their respective grooves h and i. The base F is depressed by means of the knob or handle I, operating through the perpendicular slot j in the face of 95 the case A, the spring J serving to return it to place as soon as the hand is removed from the knob. The act of depressing the knob I forces down the base F, and with it the knife-rod E and the follower H, the knife x severing 100 the end match of the card as it descends or splits them apart, according to whether

- matches which are formed in blocks or which are secured to a card are being operated upon. As soon as the knife α and follower descend below the slide on which the card of matches rests, the match that rested against the side of the follower when in its normal position between it and the knife, and which was separated from the card or split by the knife from the block as it was forced downward between it and the block of matches, is forced outward over the end of the follower by the spring-actuated lever D, acting upon the sliding block B, that bears against the inner side of the block or card. The block or card being constantly forced outward by the spring-actuated lever D, it brings another match between the knife α and the follower in position to be separated from the other matches by the knife as it is forced down.
- 20 The pressure upon the knob I then being removed, the base F is at once rapidly forced upward by the action of the spring J, the follower H pushing before it the severed match with such force that as its head is brought into frictional contact with the rough surface of the lighter L it is thereby ignited, the match being held between the lighter and the spring m below, whence it can be readily removed, if desired.
- 25 30 What I claim, and desire to secure by Letters Patent, is—
1. In a match-box, the combination, with a case adapted to receive a card or block of matches, of a spring-actuated slide for forcing the matches forward, a vertically-moving base, a knife secured thereto which passes between the matches and severs them as it is forced down, and a follower which is adapted to descend below the matches and to force them outward when it ascends, substantially as described.
  2. In a match-box adapted to receive a card of matches, the combination of a spring-actuated slide for forcing the matches forward, a vertically-moving base, a follower for forcing the matches out of the box, secured thereto at its lower end, and a vertically-moving knife for severing the matches placed inside of the follower the width of a match, whereby it is in the proper position to sever it when forced down, substantially as shown.
  3. In a match-box, the combination, with the case provided with grooves in one edge thereof, of the base, follower, and knife moving therein, the spring-actuated slide for forcing the matches forward, and a spring which engages the base and forces it upward when released, the knife and the follower being secured to the base at their lower ends, whereby they both move together in their proper relative positions, substantially as set forth.
  4. In a match-box adapted to receive matches and automatically force them out lighted, the combination of a spring-actuated slide for feeding the matches forward, a spring-actuated follower for forcing them upward out of the box, the spring-lighter L, and the spring m, both secured to the case at their lower ends, just above the exit of the match, and between which the match is held, substantially as specified.

In testimony whereof I do affix my signature in presence of two witnesses.

FRANK S. BALLARD.
